United States Patent [19]

Dawson

[11] Des. 266,151

[45] ** Sep. 14, 1982

[54] **FRACTION COLLECTOR FOR LIQUID CHROMATOGRAPHY**

[75] Inventor: **Donald Dawson**, Mt. Laurel, N.J.

[73] Assignee: **Siemens Corporation**, Iselin, N.J.

[**] Term: **14 Years**

[21] Appl. No.: **125,686**

[22] Filed: **Feb. 28, 1980**

[51] Int. Cl. .... **D10—04; D24—01**

[52] U.S. Cl. **D10/81; D10/46; D24/8**

[58] Field of Search **D10/81, 46; 422/89, 422/93; 210/656, 657, 672, 662; D24/8, 17, 99**

[57] **CLAIM**

The ornamental design for fraction collector for liquid chromatography, as shown and described.

DESCRIPTION

FIG. 1 is a top front perspective view of a fraction collector for liquid chromatography, showing my new design; and

FIG. 2 is a rear perspective view thereof.

FIG.1

FIG. 2
